UNITED STATES PATENT OFFICE

134,530

DESIGN FOR A STATUETTE

Ernest Lester Johnston, Grosse Pointe Woods,
Mich.

Application March 5, 1942, Serial No. 106,089

Term of patent 3½ years

To all whom it may concern:

Be it known that I, Ernest Lester Johnston, a citizen of the United States, residing at Grosse Pointe Woods, in the county of Wayne and State of Michigan, have invented a new, original, and ornamental Design for a Statuette of which the following is a specification, reference being had therein to the accompanying drawing, forming part thereof.

I claim:

The ornamental design for a statuette, as shown.

ERNEST LESTER JOHNSTON.
